UNITED STATES PATENT OFFICE.

THOMAS C. MCPHERSON, OF BEAVER FALLS, PENNSYLVANIA, ASSIGNOR OF ONE-HALF TO KEYSTONE WIRE MATTING CO., OF BEAVER FALLS, PENNSYLVANIA, A CORPORATION OF PENNSYLVANIA.

MAT.

No. 894,848.

Specification of Letters Patent.

Patented Aug. 4, 1908.

Application filed May 22, 1906. Serial No. 318,202.

To all whom it may concern:

Be it known that I, THOMAS C. MCPHERSON, a citizen of the United States, residing at Beaver Falls, in the county of Beaver and 5 State of Pennsylvania, have invented a new and useful Mat, of which the following is a specification.

This invention relates more particularly to metallic mats, and is in the nature of an improvement on the mat disclosed in application, Serial No. 303,507, filed Feb. 21, 1906.

The principal object in the present case is to provide novel reinforcing devices that will secure rigidity in the mat, and prevent its 15 becoming misshapen, said devices being so formed that they may be readily placed in position, will accommodate themselves to inaccuracies due to the formation of the mat strips, and will produce a more ornamental 20 effect.

In the accompanying drawings:—Figure 1 is a plan view of a portion of a mat, showing the improved reinforcements forming a part of the same. Fig. 2 is a detail horizontal 25 sectional view therethrough. Fig. 3 is a plan view of a slightly different form of mat having the reinforcements therein.

Similar reference numerals designate corresponding parts in all the figures of the 30 drawings.

In the embodiment illustrated in the first two figures, the mat is composed of sections 4, each section comprising a tortuously 35 formed sectional strip, the said sectional strip being bent into oppositely disposed open loops 5, forming longitudinal side web elements 6 and cross webs. The closed ends of the loops 5 of one section enter the open ends of the loops of the adjacent section. Pivot 40 rods 7 connect the adjacent sections, said rods thus passing through both terminals of each web element 6. So far as thus described, nothing new is claimed in the mat.

Marginal reinforcing members or devices 45 are employed in the outer loops 5 of the mat sections. These reinforcing devices consist of short looped strips 8 that are located in the end loops 5 of the sections, and are peculiarly formed, as shown. The side webs of 50 said reinforcing devices have intermediate offsets 9, and the terminal portions 10 of the webs are located alongside and abutted against the adjacent longitudinal web elements 6 of the mat section. The end webs in 55 like manner abut against the end webs of the

loops in which they are placed. One of the pivot rods 7 passes through the outer ends of said portions 10. The doubled end 11 of the reinforcing device is considerably narrower than the space between the longitudinal web 60 elements 6, and its side portions are spaced therefrom, the other pivot rod 7 extending through the doubled end, as shown so that the cross web of the reinforcement is located between the pivot rod and the cross web of the 65 loop in which said reinforcement is located.

The same reinforcements are shown in a slightly different form of mat in Fig. 3. In this structure the oppositely disposed loops 5^a of the mat sections 4^a are formed from a 70 continuous strip instead of a sectional strip, and the free ends of the end loops are separated by coiled springs otherwise the structure is substantially the same.

There are several distinct advantages for 75 the peculiarly shaped reinforcing devices. In the first place, they can be much more quickly placed in position than the devices shown in the application to which reference has been made. In forming the loops 5 and 80 5^a of the mat sections, the dies in time become worn, and consequently the width of the doubled ends will vary. With the plain U-shaped devices, such as are shown in the first application, there can be no adjustment, 85 and difficulty is sometimes encountered in inserting the same. The comparatively narrow doubled ends of the present reinforcements, however, will permit considerable variation in the width of the loops 5 and 5^a, and 90 moreover, the side webs can be more readily sprung into said loops. A still further advantage resides in the fact that the present reinforcements produce a border that is much more attractive in appearance.

From the foregoing, it is thought that the construction, operation, and many advantages of the herein described invention, will 95 be apparent to those skilled in the art, without further description, and it will be understood that various changes in the size, shape, proportion, and minor details of construction, may be resorted to without departing from the spirit or sacrificing any of the advantages of the invention.

Having thus fully described my invention, what I claim as new, and desire to secure by Letters Patent, is:—

1. In a mat, a plurality of sections comprising reversely disposed loops, certain of 110

- the doubled ends of the loops of one section being located in the open ends of the adjacent section, pivots passing through said doubled ends and being spaced from the doubled portions thereof, and reinforcements located in the end loops of each section and having side portions located against the sides of the same, said reinforcements having doubled portions engaged with the pivots and disposed in spaced relation to the sides of the section loops, in which they are located being furthermore located in the spaces between the pivots and the doubled ends of the section loops.
2. A mat comprising a plurality of sections, each section consisting of a strip formed into oppositely disposed loops having open and closed ends, reinforcing loops located in the terminal loops of each section and having open ends, the open ends of the
- section loops in which they are located being furthermore provided with closed ends of less width than the closed ends of the section loops in which they are located and abutted against said closed ends while spaced from the sides of said section loops, the closed ends of the loops of one section entering the open ends of the loops of the adjacent sections, the closed ends of the terminal loops in like manner entering the open ends of the reinforcing loops of the adjacent sections, and pivots passing through said ends and constituting connections between the various sections.
- In testimony, that I claim the foregoing as my own, I have hereto affixed my signature in the presence of two witnesses.
- T. C. McPHERSON.
